CLAIM

The ornamental design for an adapter, as shown and described.

DESCRIPTION

FIG. 1 is a perspective view of an adapter showing my new design;

FIG. 2 is a front view thereof, the rear view being symmetrical to the front view;

FIG. 3 is a cross-sectional view taken along line 3-3 in FIG. 2 thereof;

FIG. 4 is a left view thereof, the right view being symmetrical to the left view;

FIG. 5 is a cross-sectional view taken along line 5-5 in FIG. 4 thereof;

FIG. 6 is a top view thereof; and,

FIG. 7 is a bottom view thereof.

The broken lines depict portions of the adapter in which the design is embodied that are not considered part of the claimed design.

1 Claim, 7 Drawing Sheets
